(57) **CLAIM**

The ornamental design for FM transmitter, as shown and described.

DESCRIPTION

FIG. 1 is a perspective view of FM transmitter according to my new design;

FIG. 2 is a front view of FM transmitter according to my new design;

FIG. 3 is a rear view of FM transmitter according to my new design;

FIG. 4 is a left side view of FM transmitter according to my new design;

FIG. 5 is a right side view of FM transmitter according to my new design;

FIG. 6 is a top plan view of FM transmitter according to my new design; and,

FIG. 7 is a bottom view of FM transmitter according to my new design.
